(57) CLAIM

The ornamental design for a gaming table top, as shown and described.

DESCRIPTION

FIG. 1 is a perspective view thereof;

FIG. 2 is a top view thereof; and,

FIG. 3 is a side view thereof.

All four sides of the gaming table top are identical. The

The legs of the gaming table are not part of the claimed design and are not shown.
